B. REICHARD,
HAT CREASER RETAINING DEVICE,
APPLICATION FILED JULY 14, 1919.

Patented Feb. 1, 1921

Inventor
By his Attorney
Benjamin Reichard,
Geo. P. Mazz

UNITED STATES PATENT OFFICE.

BENJAMIN REICHARD, OF NEW YORK, N. Y.

HAT-CREASER-RETAINING DEVICE.

1,367,205.

Specification of Letters Patent.

Patented Feb. 1, 1921.

Application filed July 14, 1919. Serial No. 310,775.

To all whom it may concern:

Be it known that I, BENJAMIN REICHARD, a citizen of the United States, and a resident of the borough of Bronx, county of Bronx, 5 city and State of New York, have invented certain new and useful Improvements in Hat-Creaser-Retaining Devices, of which the following is a specification.

My improvements relate to devices for 10 imparting a medial longitudinal crown crease to a felt or similar soft hat body, according to the fashion at present in vogue; and the object is to attain a relatively strong positive elastic resilient clamp of light 15 weight and simple construction that is also essentially invisible in use and permanent in character, all as hereinafter more fully set forth, and described and claimed specifically.

20 In the accompanying drawings,

Figure 1, is a sectional detail of a soft hat crown illustrating the application and function of my improved creaser;

Fig. 2, is a side elevation of the creaser;

25 Fig. 3, is a top edge view thereof; and

Fig. 4, is a transverse section taken upon plane of line 4—4, Figs. 2 and 3.

My crease holder or clamp is made of a single piece of relatively thin celluloid bent 30 over upon itself and permanently set, and consisting of the curved spine *c*, and side members or wings *c'*, *c'*, the longitudinal edges *c²*, *c²*, of which constitute jaws which tend constantly to contact with each other, 35 and hence to clamp any material inserted between them. In other words the device is inherently elastic and resilient,—the resilience of the spine *c*, particularly insuring permanence to the function of the jaws *c²*, 40 *c²*, in binding together the thicknesses of hat body interposed between them and constituting the crown crease in such manner that the contacting material is firmly and positively pinched and held against slip or 45 displacement, as will be readily understood by reference to Fig. 1, of the drawing.

I preferably make my hat creasing device of transparent celluloid, so that when in position on the inner side of the crown of 50 the hat it is practically invisible except upon close inspection, because it transmits the color of the material to which it is applied. This obviously is a decided advantage, since the use of such an expedient for shaping a 55 hat crown is presumably *sub rosa*. The

lightness in weight of the material of which my improved creasing device is formed is also an important factor, especially when used in high grade hats of fine quality and texture.

60

I am aware that hat crease-retaining devices have been made of sheet metal, but these are not resilient nor reliable, as they soon work loose and become inoperative under the exigencies of actual use.

65

By the use of the term "celluloid" herein I mean to include any non-metallic substance or equivalent of celluloid adapted to my purpose, such as a composition of gelatin, lactic acid, etc., which forms a transparent elastic clip, which is, to all intents and purposes, invisible.

70

What I claim as my invention and desire to secure by Letters Patent is,

1. A hat-crease-retaining device of the 75 character designated, formed of a single piece of non-metallic elastic resilient material with its free edges normally tending to approach each other to grip the crease at such edges only.

80

2. A hat-crease-retaining device of the character designated, formed of a single piece of transparent non-metallic elastic resilient material with its free edges normally tending to approach each other to grip the 85 crease at such edges only.

3. A hat-crease-retaining device of the character designated, formed of a single piece of elastic resilient celluloid having a permanent set with its free edges normally 90 tending to approach each other to grip the crease at such edges only.

95

4. A hat-crease-retaining device of the character designated, formed of a single piece of transparent elastic resilient celluloid having a permanent set with the free edges normally tending to approach each other to grip the crease at such edges only.

100

5. The hat-crease-retaining device shown and described, formed of a piece of transparent, elastic resilient, non-metallic material bent upon itself and permanently set, and comprising a curved spine to receive the bend in the crown of the hat and side wings the longitudinal edges of which constitute jaws tending to constantly yieldingly contact with each other and clamp the material of the hat at the crease between them.

105

6. As an improved article of manufacture, a hat-crease-retaining device formed of a 110

single piece of resilient material bent upon itself to form a curved spine to loosely embrace the fold of the hat crown and having side portions the longitudinal edges of 5 which only pinch the crown fold between them, said edges normally tending to constantly approach each other to form a grip.

7. A device of the class described comprising a strip bent upon itself to provide 10 a pair of jaws with the edges of the jaws normally tending toward each other to provide gripping jaws.

8. A hat-crease-retaining device of the character described, comprising a one-piece 15 structure of transparent, elastic resilient

non-metallic material bent upon itself and permanently set to form a hollow spine portion adapted to contain without pressure thereon the bight of the hat crease and with relatively convergent side wings, the longitudinal edges of which constitute pinching jaws which tend constantly to yieldingly contact with each other and clamp the material constituting the sides of the hat crease between them.

BENJAMIN REICHARD.
